UNITED STATES PATENT OFFICE

163,184

RADIANT HEATER OR SIMILAR ARTICLE

Paul A. Jones and Roy G. Churan, Chicago, Ill.,
assignors to Inland Steel Container Company,
Chicago, Ill., a corporation of Illinois

Application February 10, 1951, Serial No. 14,170

Term of patent 14 years

(Cl. D81—10)

To all whom it may concern:

Be it known that we, Paul A. Jones and Roy G. Churan, citizens of the United States and residents of Chicago, in the county of Cook and State of Illinois, have invented a new, original, and ornamental Design for a Radiant Heater or Similar Article, of which the following is a specification, reference being had to the accompanying drawing, forming a part thereof.

In the drawing,

Figure 1 is a front view of a radiant heater or similar article, showing our new design;

Figure 2 is a top plan view of the same;

Figure 3 is an end view, both ends being substantially the same; and

Figure 4 is a vertical sectional view.

We claim:

The ornamental design for a radiant heater or similar article, substantially as shown and described.

PAUL A. JONES.
ROY G. CHURAN.
